UNITED STATES PATENT OFFICE.

LUTHER PROFITT, OF MANCELONA, MICHIGAN.

STEAM-ENGINE REVERSING-GEAR.

1,109,462.

Specification of Letters Patent. Patented Sept. 1, 1914.

Application filed December 16, 1913. Serial No. 807,149.

To all whom it may concern:

Be it known that I, LUTHER PROFITT, a citizen of the United States, residing at Mancelona, in the county of Antrim and State of Michigan, have invented new and useful Improvements in Steam-Engine Reversing-Gears, of which the following is a specification.

This invention relates to steam engine reversing gear, the object in view being to produce a simple and effective reversing gear for steam engines, doing away with a number of operating parts of the reversing gear now in common use in connection with steam engines.

With the above and other objects in view, the invention consists in the construction, combination and arrangement of parts, as will hereinafter be more fully described, 20 illustrated and claimed.

In the accompanying drawings:—Figure 1 is a side elevation of a stationary steam engine showing the reversing gear of this invention applied thereto. Fig. 2 is a detail 25 perspective view of the link and its operating fork.

Referring to the drawings 1 designates the engine base, 2 the cylinder, 3 the steam chest, 4 the steam supply pipe and 5 the 30 throttle valve casing.

6 designates the crank shaft which in carrying out the present invention has fast thereon a cam disk 7 provided in one face thereof with a cam groove 8.

35 9 designates the crosshead guide, 10 the sliding crosshead reciprocating therein and 11 the connecting rod interposed between the sliding cross head and the crank shaft.

In carrying out the present invention, the 40 valve operating link 12 which is coupled to the slide valve stem 13 by means of a connecting rod 14 is provided with a double fork 15 extending in a direction substantially perpendicular to the major axis of the 45 link 12, said link being pivotally mounted at the point 16 on a suitable supporting post or bracket 17. The fork 15 is provided with two sets of slots 18 and 19, one set of slots being adapted to receive one end of a link

rocking lever 20 while the other set of slots 50 are designed to receive pins 21 extending laterally from opposite sides of the lever 20. The lever 20 is fulcrumed at the point 22 intermediate its ends on a suitable fulcrum post 23 and is provided at its outer extremity 55 with a pin or roller 24 which moves lengthwise of the cam groove 8 in the disk 7 above referred to, thus producing a rocking movement of the lever 20 and causing the opposite end thereof to impart a rocking movement to the fork 15 and hence to the valve operating link 12.

The connecting rod 14 is formed with a longitudinal slot 25 which receives a pin on a vertically movable rod 26 which is attached to the short arm 27 of an elbow lever, the other and longer arm 28 of said lever being provided with an operating handle 29 and a thumb latch 30 which engages the teeth of a segmental rack 31 fastened to 70 a stationary part of the engine.

From the foregoing description, taken in connection with the drawings, it will now be seen that by moving the lever 29 in one direction or the other along the rack 31, 75 the connecting rod 14 is moved to either end of the link 12, the said connecting rod 14 carrying a sliding block 32 movable lengthwise of and within the link 12. In this way the slide valve may be reversed and the direction of rotation of the engine correspondingly reversed whenever found necessary. One or more suitable guides 33 may be provided to direct and steady the rocking movement of the lever 20, one of such guides being shown as fastened to the crosshead 80 guide 9.

What I claim is:—

In reversing gear for steam engines, the combination with the steam cylinder, cross head guides, steam valve and crank shaft, of a cam disk fast on said crank shaft and provided with a cam groove, a valve operating link fulcrumed on the cross head guide and having its axis parallel to the axis of said crank shaft, a connecting rod between said link and the stem of said valve, a fork extending laterally from said link

and provided with two slots intersecting each other at right angles, a link rocking lever having one end slidable in one of said slots and a pin slidable in the other slot of said fork and the other end provided with a runner working in said cam groove, and a reversing thumb latch lever operatively connected with said connecting rod for shifting

the point of engagement between said rod and the valve operating link.

In testimony whereof I affix my signature in presence of two witnesses.

LUTHER PROFITT.
